UNITED STATES PATENT OFFICE.

PENROSE R. HOOPES AND FRITZ HESS, OF HARTFORD, CONNECTICUT; SAID HESS AS SIGNOR TO SAID HOOPES.

VENDING MACHINE.

Application filed April 20, 1927. Serial No. 185,257.

The present invention relates to an apparatus for vending or dispensing articles of merchandise, such as rolls or bars of candy or other confections.

5 The aim of the invention is to provide an apparatus of this sort having various features of novelty and advantage.

More particularly, the object of the invention is to provide a simple, economic and effective apparatus of this sort wherein the articles to be dispensed or vended are supported in a magazine or carrier in such manner that they may be positively brought into registry with an opening without danger of 15 the articles interfering with the proper operation of the device. Our improved arrangement is such that the magazine can be moved but one step at a time, and the magazine cannot be raised or lowered except by operating 20 the controlling mechanism in the proper manner.

Other objects will be in part obvious and in part pointed out more in detail hereinafter.

25 The invention accordingly consists in the features of construction, combination of elements and arrangement of parts which will be exemplified in the construction hereinafter set forth, and the scope of the application of which will be indicated in the appended claims.

In the accompanying drawings, wherein we have shown, for illustrative purposes, one embodiment which the present invention may 35 take, it being understood that this disclosure is by way of illustration only and that our invention is susceptible of various modifications and changes:

Figure 1 is a front elevational view with 40 one side of the apparatus broken away along the line 1-1 of Fig. 2;

Fig. 2 is a sectional view taken longitudinally and centrally through the apparatus;

Fig. 3 is a front view of the cams for operating the slides which control the magazine;

Fig. 3a is a side view of the male cam;

Fig. 4 is a horizontal sectional view taken substantially on line 4-4 of Fig. 1;

50 Fig. 5 is a view similar to Fig. 4 but taken on line 5-5 of Fig. 2;

Fig. 6 is a sectional view taken substantially on line 6-6 of Fig. 5 and shows one of the controlling slides in retracted or locking 55 position;

Fig. 7 is a view similar to Fig. 6 but showing the slide advanced so as to permit the magazine to move down one step; and

Fig. 8 is an enlarged detail sectional view taken substantially on line 8-8 of Fig. 5. 60

Referring to the drawings in detail, 10 designates an upright casing of any suitable shape and construction. This casing is illustrated as having a front cover 11 hinged at the top, as at 12. This cover may carry, 65 adjacent its lower end, a lock 13 of any suitable sort. The cover may have an opening 14 through which access may be had to the articles to be dispensed. Preferably, the edge of this opening is flanged, as at 15, so 70 as to provide a smooth edge and thus avoid injury to the person taking the merchandise from the casing. This opening 14 is located substantially midway between the upper and lower ends of the casing. Immediately above 75 the opening 14 is a sight opening 16 into registry with which a sign 17 is adapted to be brought when the magazine has been brought to its lowermost position. This sign carries the word "Empty" so as to advise anyone contemplating operating the device that the articles to be dispensed have been depleted. The cover further carries a bearing member 80 18 in which is journaled the shaft or shank of the male cam for operating the device, as 85 hereinafter described more in detail.

At each side of the casing are a pair of slots or grooves 20 which may be formed in any suitable manner, as by means of strips 21 suitably secured to the side walls of the casing. 90

Mounted for vertical movement within the casing and guided in part by the grooves 20 is a magazine having superimposed compartments formed by spaced apart shelves 25. These shelves may be formed in any suitable manner, but they are here shown as being constructed of sheets of metal with their edges down-turned so as to form flanges 26. The shelves 25 are fixed to a member preferably formed of sheet metal and having a back 27 and side walls 28, 28. The magazine in horizontal section corresponds generally in shape to the casing, except that it is narrower so as to fit in between the guide strips 21. The shelves are riveted to the side walls 28 by 100 means of pins 29, these pins having heads 30 which engage in the grooves 20 so that the magazine is properly guided in its vertical movements. On the top of the magazine is the "Empty" sign 17. The distance between 105 110

the lower edge of the flange 26 of one shelf and the top of the next subjacent shelf is at least as great as the height of the opening 14 so that, in any position of the magazine, access can be had to but that compartment which is in registry with the opening 14. Obviously, the magazine may be provided with any desired number of compartments and, while I have shown but three such compartments in the present illustrative disclosure, in actual practice more than three can be used to advantage. The height of the casing is substantially twice the height of the magazine minus the height of one compartment so that when the lowermost compartment is in registry with the opening 14, the upper end of the magazine is adjacent the top of the casing and, when the uppermost compartment is in registry with the opening 14, the lower end of the magazine is adjacent the bottom of the casing.

Movement of the magazine is controlled by one or more slides located between the magazine and the side walls of the casing and in the planes of the guide grooves 20. In the present illustrative disclosure, I have shown two such slides, one at each side of the magazine and suitably connected together so as to be moved in unison. A description of one of these slides is applicable to the other. The slides, indicated generally by the letter A, are supported for sliding movement on blocks 31 suitably secured to the side walls of the casing, and the forward vertical guiding members 21 are cut away, as shown most clearly in Figs. 5 and 6, so as to accommodate these slides. The rear ends 32 of the slides are adapted to abut against the rear guide strips 21 when the slides are in the locking position shown in Figs. 2 and 6. Each slide has, adjacent its forward end and on its inner face, a groove, 33 inclined downwardly and forwardly, the rear wall 34 of each of these grooves being preferably smooth, and the forward wall 35 being serrated or stepped so as to form downwardly facing abutments 36. The grooves 33 are of such depth that the heads 30 of the pins associated with the two lower shelves may pass through the grooves, but the pins associated with the shelf forming the bottom of the upper compartment cannot pass through these grooves. Thus, after the uppermost compartment has been brought into registry with the opening 14, further downward movement of the magazine, upon operation of the slides, is avoided. The grooves 20 in the forward guide strips and immediately above and below the slide are flared, as at 37, so as to insure against the pins catching on shoulders when the apparatus is properly operated. Each of the slides is further provided, rearwardly of the grooves 33, with relatively wide vertical grooves 40, the purpose of these grooves 40 being to permit the magazine to be manually

raised after the cover 11 has been swung up and the slides drawn forwardly to a position where the grooves 40 register with the front guide grooves 20. The slides are normally urged into the retracted or locking position shown in Figs. 2 and 6 by springs 41 respectively connected at their opposite ends to rivets 42 and 43 respectively carried by the slide and the rear guide strips 21. The slides may be grooved, as at 44, so as to accommodate these springs.

The forward ends of the slides are connected together by a spider 45 having a central hub 46 having an internal cam surface or partial thread 47. Adapted to cooperate with this cam surface is a complementary male cam 48 carried by a shank 49 journalled in the bearing member 18 carried by the cover 11. Fixed to the outer end of the shank 49 is an operating knob 50. By preference, the bearing member 18 has a cylindrical skirt 51 in which the hub 46 has a sliding bearing. This skirt may be cut away as at 52 so as to accommodate the arms of the spider when the slides are moved to the advanced position shown in Fig. 7.

Obviously, the apparatus may be provided with a check or coin controlled device so associated with the operating mechanism that this mechanism cannot be operated to permit the magazine to drop down one step until after a coin of the proper denomination has been inserted into the check controlled device.

The operation of the apparatus is briefly as follows: Assuming that the magazine has been filled and is in its uppermost position, the lowermost pins 30 will rest upon the slides A forwardly of the grooves 33. The lowermost compartment will then be in registry with the opening 14. To gain access to the merchandise in the middle compartment, the magazine is caused to move down one step to the position shown in Fig. 2 and this is done by turning the knob 50 thereby causing, through the cams 47 and 48, the slides to move forwardly to the position shown in Fig. 7 and in which position the lowermost pins enter the grooves 33. After the pins enter these grooves, the springs 41 move the slides to the retracted position shown in Fig. 6 so that the pins, which have been engaged in the grooves 33, may move to the position shown in Fig. 6. As the slides are thus retracted, the lower ends of the forward grooves 20 are blanked by the slides so that the magazine can move downwardly but one step at a time. It will further be noted that, owing to the serrated forward walls 35 of the grooves 33, the magazine cannot be raised without first removing the cover 11 and then manually pulling the slides forwardly so that the grooves 40 thereof register with the forward grooves 20. To cause the magazine to move down another step, so that the uppermost compartment is in registry with the opening 14, the knob 50

is given another turn. Thereafter, although the knob may be further operated, the magazine will not move down any further because the pins 30 associated with the bottom of the 5 upper compartment are too long to enter the grooves 33. After the magazine has been depleted, it may be raised by swinging up the cover 11 and pulling forwardly on the slides until the grooves 40 register with the 10 front grooves 20.

We claim as our invention:

1. In an apparatus of the character described, a casing provided with an opening, a gravity magazine therein having superimposed compartments arranged to be brought successively into registry with said opening, a slide for controlling the movement of said magazine and arranged upon each operation thereof to limit the movement of said 20 magazine, means for operating said slide and positive means for preventing reverse movement of said magazine.

2. In an apparatus of the character described, a casing provided with an opening, a 25 magazine therein having superimposed compartments arranged to be brought successively into registry with said opening, a slide for controlling the movement of said magazine and arranged upon each operation thereof to limit the movement of said magazine to the height of one compartment, said operable slide normally preventing movement of said magazine in all directions, and means for operating said slide.

3. In an apparatus of the character described, a casing provided with an opening between its ends, a magazine therein adapted to be fed down by gravity and having superimposed compartments arranged to be brought successively into registry with said opening, a slide movable at right angles to said magazine for controlling the movement of said magazine and arranged upon each operation thereof to limit the extent of movement of the magazine, said slide having means for preventing the magazine from being moved upwardly, and means for operating said slide.

4. In an apparatus of the character described, a casing provided with an opening between its ends, a magazine within the casing having a plurality of superimposed compartments, said magazine having vertically spaced apart projections, a slide adapted to cooperate with said projections to hold said magazine in predetermined positions, said slide having an inclined slot through which the projections are adapted to move upon operation of the slide, and means for moving 60 said slide.

5. In an apparatus of the character described, a vertical casing, a magazine therein having a plurality of superimposed compartments, a slide for controlling the movement 65 of said magazine and having an inclined

groove, vertical spaced apart projections on said magazine and arranged to rest upon the top of said slide when the latter is in normal position, and means for operating said slide to bring the upper end of said groove 70 into registry with the line of movement of said projections, said slide being movable towards normal position after a projection has entered the groove thereof.

6. In an apparatus of the character described, 75 a casing having an opening, a magazine therein having a plurality of superimposed compartments, vertically spaced apart projections on said magazine, a slide between said magazine and casing and having an inclined groove, means for advancing the slide to bring the upper end of said groove into registry with the line of movement of said projections, and means for retracting said slide to normal position, said slide being 80 substantially as high as the distance between said projections, one of said projections being of such length as to be unable to pass through said groove whereby to hold the uppermost compartment in registry with said 85 opening, the projections beneath said mentioned projection being of such length as to pass through said groove on proper operation of said slide.

7. In an apparatus of the character described, 90 a vertical casing having an opening between its ends, a magazine within said casing having a plurality of superimposed compartments arranged to be successively brought into registry with said opening, a slide between said casing and magazine and having an inclined groove the forward wall of which is serrated to provide downwardly facing abutments, projections on said magazine adapted to pass downwardly through 95 said groove when the slide is operated, and means for operating said slide.

8. In an apparatus of the character described, 100 a vertical casing provided with an opening between its ends, a magazine within said casing having a plurality of superimposed compartments adapted to be successively brought into registry with said opening, a slide mounted between said casing and magazine and having a downwardly and forwardly inclined groove the forward wall of which is serrated, said slide also having a vertical groove rearwardly of said inclined groove, projections on said magazine adapted to pass through said inclined groove when 105 the latter is operated, said magazine also having a projection arranged not to pass through said inclined groove whereby said slide will hold said magazine against further downward movement after the uppermost compartment has been brought into registry with said opening, and means for operating said slide.

9. In an apparatus of the character described, 115 a vertical casing provided in its

front wall and between its ends with an opening, a magazine within said casing and having superimposed compartments arranged to be brought successively into registry with said opening, guide grooves in the sides of said casing, vertically spaced apart projections on said magazine engaging in said grooves, a slide intercepting one of said grooves and having an inclined groove the upper end of which is adapted to be brought into registry with the intercepted slide groove, means for moving said slide forwardly, and spring means for retracting said slide.

10. In an apparatus of the character described, a vertical casing having an opening in its front wall and between its ends, a gravity magazine mounted therein and having a plurality of superimposed compartments, a horizontally movable slide for controlling the movement of said magazine, a spiral cam less than 180° associated with said slide, an operating cam complementary to said first cam and adapted to cooperate therewith to advance said slide, and means for normally urging said slide to retracted position.

11. In an apparatus of the character described, a casing provided with an opening in its front wall and between its ends, a gravity magazine in said casing having superimposed compartments arranged to be successively brought into registry with said opening, a pair of slides one at each side of said magazine and arranged to control the movement of said magazine, means for connecting said slides together, and means for operating said slides.

12. In an apparatus of the character described, a casing provided with an opening between its ends, a magazine within said casing having a plurality of superimposed compartments adapted to be brought successively into registry with said opening, said magazine having at each side a vertical row of spaced apart projections, a pair of slides one to each side of said magazine, each of said slides having an inclined slot adapted to be brought into registry with the respective lines of movement of said projections, and means for operating said slides in unison.

50 13. In an apparatus of the character described, a vertical casing, a magazine therein

having a plurality of superimposed compartments, a vertical row of spaced apart projections on each side of said magazine, a pair of slides one to each side of said magazine, said slides having inclined grooves adapted to accommodate the respective rows of projections, a cam for moving said slides in unison to bring the upper ends of said grooves into the line of movement of said projections, and means normally urging said slides to retracted position.

14. In an apparatus of the character described, a casing provided in its front wall and between its ends with an opening, a gravity magazine within said casing having a plurality of superimposed compartments arranged to be brought successively into registry with said opening, said magazine having at each side a vertical row of spaced apart projections, a pair of slides one at each side of said magazine, said slides having forwardly and downwardly inclined grooves the forward walls of which are serrated, said grooves and projections being so arranged that the projections which position all but the uppermost compartment in registry with said opening may pass through said grooves upon successive operations of said slides, and the projections which position the uppermost compartment in registry with said opening cannot pass through said grooves, a spider connecting the forward ends of said slides and having a hub provided with a cam, and an operating cam carried by said casing and operating with said first mentioned cam for moving said slides.

15. In an apparatus of the character described, a casing having a pivoted forward cover, guideways on the sides of said casing, a vertically movable magazine in said casing, a slide controlling the movement of said magazine and adapted to receive said projections when said slide is moved forwardly, and cam means for operating said slide, said cam means comprising a plurality of separable parts, one of said parts being carried by the slide and the other by said cover, said parts being in engagement when said cover is closed.
